UNITED STATES PATENT OFFICE.

HAROLD L. PALMER, OF UTICA, NEW YORK.

DESIGN FOR A CUFF-BUTTON.

SPECIFICATION forming part of Design No. 28,443, dated April 5, 1898.

Application filed February 15, 1898. Serial No. 670,437. Term of patent 7 years.

To all whom it may concern:

Be it known that I, HAROLD L. PALMER, a citizen of the United States, residing at Utica, in the county of Oneida and State of New York, have invented and produced a new and original Design for Cuff-Buttons, of which the following is a specification, reference being had to the accompanying drawings, forming a part thereof, in which—

Figure 1 is a side elevation of a cuff-button embodying the features of my design, and Fig. 2 is a plan view of the same.

The leading feature of the design consists

in a Y-shaped shank A, having a head B at each extremity of its diverging members and a third head C at its base. In detail the heads B at the branch of the shank are conical and the base-head C is of the button type.

I claim—

The design for the cuff-button herein shown and described.

HAROLD L. PALMER.
